**HIGH PRESSURE HIGH TEMPERATURE
PUNCH MEMBER**

Robert H. Wentorf, Jr., Schenectady, N.Y., assignor to
General Electric Company, a corporation of New York
Filed Mar. 26, 1963, Ser. No. 268,096
2 Claims. (Cl. 18—16)

This invention relates to a high pressure, high temperature apparatus punch member and more particularly to such a punch member having a very hard material nib projection on the working end or face thereof.

In general, high pressure high temperature apparatuses utilize a plurality of pressure resisting members, one or more of which move towards another to define a reaction chamber in which a specimen material is placed to be subjected to high pressures and high temperatures. The ends of these pressure resisting members are subjected to extreme temperatures and pressures and thus to critical stresses which cause many failures to occur at the very ends of the punch members. These failures usually encompass only a very small portion of the end area and volume. Such a small failure yet results in the necessity of replacing the entire punch assembly which is usually of a very high strength, high cost, and difficult-to-work material.

Accordingly, it is an object of this invention to provide an improved punch member.

It is another object of this invention to provide a high pressure high temperature punch member with a separable end portion.

It is another object of this invention to provide a nib projection on the tip of a high pressure high temperature punch member.

It is another object of this invention to provide a refractory nib projection on the end of a high pressure high temperature punch member.

Briefly described this invention includes a refractory nib projection on the end of a tapered, hard metal punch member, which follows the general contour of the tapered punch member and extends the punch face to a new face on the nib projection which is of smaller cross sectional area than the face of the hard metal punch member.

This invention will be better understood when taken in connection with the following description and the drawing in which:

FIG. 1 is an illustration of the nib member of this invention as applied to a punch member having tapered and arcuate surfaces;

FIG. 2 is an illustration of a nib member according to the practices of this invention when applied to a punch member of generally angular cross section; and

FIG. 3 is an illustration of one use of nib members between a plurality of lateral punches.

Two general types of high pressure high temperature apparatuses to which this invention is particularly applicable are disclosed in U.S. Patents 2,941,248—Hall and 3,107,395—Bundy, assigned to the same assignee as the present invention. The “belt” apparatus disclosed in the aforementioned Hall patent, comprises in one embodiment, a pair of oppositely positioned frustoconical punch members which move into a convergent divergent opening in an intermediate concentrically positioned die or belt member. A specimen material in the die member and between the punches is compressed by motion of the punches towards each other.

The apparatus disclosed in the aforementioned Bundy patent comprises a reaction chamber defined by the smaller end faces of a plurality of trapezoidal punch members, for example six, all of which move towards a defined center and interfit with each other to define a

2

reaction chamber. A specimen material is placed in the reaction vessel to be subjected to high pressures and high temperatures. A ceramic or stone material gasket is employed in these apparatuses between all punches, 5 where applicable, and between the punches and the belt or die in the belt apparatus.

In either of the above described apparatus, the punch faces, i.e., the inner faces which define the walls of the reaction vessel, are subjected to the highest pressures, 10 the highest temperatures, and the highest critical stresses. It is thus an important practice that thermal insulation, in the form of ceramic or stone gasketing, be employed between the punch face and the center of the reaction vessel in order to shield the punch face from the high 15 temperatures in the reaction vessel. It is also an important feature and a matter of standard practice to enclose the side surfaces of the punch members with ceramic or stone gasket materials to adequately support the punch face. In most instances this practice is included in the 20 use of gasketing between punches or between punches and confining members.

Under the conditions of high pressures and high temperatures, even such materials as the cemented tungsten carbides become somewhat plastic and are subject to failure. 25 These failures are usually evidenced by cracks in the punch face or by small sections of the punch face breaking off. One cause of such failures is loss of lateral support at the punch face which exerts extraordinarily high forces on the punch causing a material flow and failure. A primary contributing factor to these failures is the exposure of the punches to the very high temperatures in the sample which substantially weakens the punch material. Severe limitations are imposed on 30 the distance from the punch to the specimen because, for example, added materials diminish pressure generation ability of the apparatus or contribute prohibitive gasketing problems.

It has been discovered that a small nib of a refractory material, for example alumina, cubic boron nitride, beryllia, or zirconia may be attached to the punch faces and positioned between the punch faces and the specimen or 40 the reaction vessel. The nib is more resistant to high temperatures while at the same time replaces gasket or reaction vessel material to provide higher pressures with less stroke or punch travel. However, where very high 45 temperatures are not a problem or are not utilized, the nib of this invention may be metallic. In any event the use of nibs precludes the necessity of replacing the entire punch member in those very high pressure high temperature operations where punch breakage is common. Cermet materials may also be utilized for these nibs.

One particular example of the practice of this invention is illustrated in FIG. 1. Referring now to FIG. 1, there is illustrated a punch member 10 such as shown 55 in the aforementioned Hall patent. Punch member 10 comprises a cylindrical base structure 11 and a tapered or frustoconical portion 12 extending from the base 11. Nib 13, in accordance with the practice of this invention, is placed on the face 14 of punch 10. This nib portion 60 13 includes a side surface 15 which is smoothly integrated with the contour of punch portion 12. Surface 15 follows the same projecting pattern of punch portion 12 to provide a face portion 16 which is smaller than face portion 14 of punch portion 12. For example, a 65 frustoconical punch includes, preferably, a frustoconical nib where the nib is a graphical projection of the frustoconical configuration of the punch. The side surface of the nib may, however, be a smooth curve tangentially engaging the outline curve of the tapered surface of the punch.

The longitudinal extension of the thickness of such a nib 13 is restricted to be as small as possible commen-

surate with the axial dimension of ordinary tip failures of the punches. The thickness must be maintained of a minimal dimension because the refractory material needs more support by way of gasket materials to maintain a structural integrity than do the hard steels and cemented carbides of which the punch members are usually made. Accordingly the nib projection must be continually supported over its entire thickness. In a belt type apparatus, the effective gasketing between the punch and die member must extend along the punch and die members a distance greater than the extension or thickness of the nib. The same practice is true of interfitting punch assemblies where the gasket therebetween must be axially longer than the thickness of the nib.

In FIG. 2, there is shown a prism or trapezoidal punch 20 wherein a small nib 21 is positioned on the face 22 of punch 20 as an extension thereof. Nib 21 defines a face portion 23 smaller than face portion 22 of punch 20. The purposes for which nib 21 is employed are the same as those described for FIG. 1.

FIG. 3 illustrates four punches 24, 25, 26, and 27 (each similar to punch 20 of FIG. 2), circumferentially arranged to define a reaction chamber or zone 28. In a 6-punch assembly, as disclosed in the aforementioned copending Bundy application, the present four punches 24-27 are generally denoted as the lateral or horizontal punches defining the side walls of a rectangular reaction vessel, and a pair of vertical punches, not shown, define the top and bottom wall of a reaction vessel. Each punch 24-27 includes a nib projection 29, 30, 31, and 32, respectively, at the punch faces. In one example, suitable gaskets 33, 34, 35, and 36 are positioned between the punches 24-27 and extend from the reaction zone 28 a considerable distance beyond the nibs. These gaskets may terminate at the end of the nib, or, as illustrated, may extend further towards the reaction zone to define the walls of the zone. In the latter instance, further thermal insulators 37, 38, 39, and 40 are employed at the ends of the nibs as filler elements.

Particular advantages of the use of such a nib in the practice of this invention are:

- (1) Relatively compressible insulating stone material is replaced by rather incompressible nib material so that the punches need not travel as far to produce high pressure in the reaction zone, and thus the demands upon the gasketing material are less severe.
- (2) The nibs aid in concentrating the force from the punch face to the reaction zone, after the manner of a tapered punch so that the pressure is higher at the nib face in the reaction zone than on the punch face. Because the nibs are exposed to high pressure on all sides, their strength and ductility, insofar as their refractory material is concerned, are improved, and relatively brittle but high strength refractory materials can be used for the nibs.

(3) For a given reaction zone pressure, the total length of the gasket is increased over that ordinarily used. Thus, the average pressure on the gradient in the gasket is reduced and the local stresses on the punches are also reduced.

(4) The nib material receives the brunt of the severe stress and thermal gradients. However, they are small, economical, and easily replaced.

In the practices of this invention, the nibs are usually employed by being fastened to the corresponding faces of the punches. Such fastening, however, should not take the form of any opening in the nib or in the punch such as for bolts, attaching flanges, etc. The use of the nibs in this invention has been limited to semipermanent attaching means in the form of various glues and cements, such as rubber glues, epoxy resin, etc., which do not impose any undue stress concentrations on either the nib or the punch through any material removal.

While a specific method and apparatus in accordance with this invention is described and shown, it is not intended that the invention be limited to the particular description nor to the particular configurations illustrated, and it is intended by the appended claims to cover all modifications within the spirit and scope of this invention.

What I claim as new and desire to secure by Letters Patent of the United States is:

1. In a high pressure apparatus wherein a plurality of punches are arranged in opposed relationship with suitable gasket material contiguous with each punch whereby movement of at least one punch causes compression of the gasket material and transmits high pressure to a closed reaction vessel, the improvement comprising:

(a) a nib positioned on and extending from the distal end of each of said punches inwardly toward the closed reaction chamber,

(1) each of said nibs being harder than the material comprising said punches and the base area of each nib being similar to and in mating relationship with the face of the distal end of its respective punch.

2. The improvement substantially as recited in claim 1 wherein each nib is composed of refractory material.

UNITED STATES PATENT OFFICE
CERTIFICATE OF CORRECTION

Patent No. 3,191,231

June 29, 1965

Robert H. Wentorf, Jr.

It is hereby certified that error appears in the above numbered patent requiring correction and that the said Letters Patent should read as corrected below.

Column 4, line 39, strike out "and the" and insert instead --, each nib tapering from a --; line 40, strike out "of each nib being"; line 42, after "punch" insert -- to a terminal face having an area smaller than said base area --.

Signed and sealed this 21st day of December 1965.
